UNITED STATES PATENT OFFICE.

ALFRED CORNELL, OF TONBRIDGE, ENGLAND.

DEVICE FOR USE IN SHARPENING DOMESTIC AND OTHER KNIVES.

1,342,275.

Specification of Letters Patent. Patented June 1, 1920.

Application filed July 2, 1918. Serial No. 243,082.

To all whom it may concern:

Be it known that I, ALFRED CORNELL, a subject of the King of Great Britain, and resident of Tonbridge, in the county of Kent, England, have invented new and useful Improvements Relating to Devices for Use in Sharpening Domestic and other Knives, of which the following is a specification.

10 This invention relates to devices for sharpening cutting instruments of the type in which the reciprocation of the blade of the instrument upon or between the surface or surfaces of the sharpening means for the purpose of sharpening or renewing the cutting edge thereof causes the rotation of the cutter or sharpening means; the object of the present invention being to provide an improved device or apparatus of the kind referred to applicable for use in sharpening domestic or table and other knives, where- 20 by the operation of sharpening is accomplished expeditiously and efficiently and, being of a simple character, is also capable of 25 production at low cost.

According to this invention the device comprises a disk or wheel of carborundum or other sharpening material having a V-shaped peripheral groove and arranged in such a manner that the action of drawing the knife across the V-shape sharpening surface effects the rotation of the disk or wheel and the sharpening or renewing of the cutting edge of the knife. The aforesaid disk or wheel is mounted on a shaft or spindle the latter working in bearings carried on a suitable base or support.

The knife to be sharpened is inserted between the faces of the V-shape groove and is guided and held against the sharpening surface by any suitable means such for example as rotatable members situated at opposite sides of the axis of the disk or wheel. The said guides may be of a resilient character or be constructed of wood or other suitable or convenient material. The guides may however be constituted by a dome or cover of metal, wood or other suitable material or be in the form of a rim surrounding the sharpening disk or wheel, cross slots being formed in the cover or rim for the reception of the knife so as to insure the same being always presented in the required angular position in relation to the V-shape sharpening surface. The disk or wheel may

be formed in one piece or be constituted by a bi-part structure with a washer of leather or other suitable material arranged between the parts composing the disk or wheel. These parts may moreover be rendered in- 60 interchangeable and reversible so as to lengthen the life of the disks. In the latter case each of the faces of the disks are chamfered so as to present a more or less sharp edge or periphery. 65

In order that the invention may be readily understood and carried into effect I will describe the same with reference to the accompanying drawings wherein:—

Figure 1 is an end view of the apparatus 70 and

Fig. 2 a corresponding plan.

Fig. 3 is a view showing a modified form of disk or wheel.

Fig. 4 is a plan view showing the apparatus provided with a modified form of guide. 75

A disk or wheel *a* of sharpening material having a V-shape groove formed in its periphery is mounted on a shaft or spindle *b* which is capable of rotation in the bearings *c* secured to the base or support *d*. The said disk or wheel may be formed in one piece as hereinbefore described, and as shown in Figs. 1 and 2, and may be clamped 80 between washers or collars *e*, *e*; or the construction may be that illustrated in Fig. 3, in which it is constituted by a pair of disks *a'*, *a'*, each disk being a replica of the other and having a washer *a*² which may be made 85 of leather interposed between the adjacent faces of the parts. The disk or wheel so constituted has its faces chamfered so as to present a more or less sharp edge or periphery. The disks are thus rendered reversible 90 or interchangeable so that the sharpening surfaces may be changed and the life of the disks lengthened. The separate halves of the disks *a'*, *a'* and the washer *a*² are clamped on the spindle *b* between the 100 washers *e*, *e*. The leather washer will not be found objectionable as it will not be detrimental to the sharpening effect of the disk on the knife edge. At the open ends of the V-shape groove and at diametrically 105 opposite points are guides for directing the knife against the sharpening surfaces same comprising members each of which may consist of a sleeve or cone *f* of rubber or other resilient material adapted to rotate 110

by the passage of the knife blade over its surface. The sleeve *f* is placed about a pin *g* formed or provided on a plate *h* which is secured to the base or support *d*. The rotatable sleeves or cones may be formed of wood or other suitable or convenient material. These members are so placed relatively to the V-groove in the disk or wheel *a* as to insure that the cutting edge of the knife shall engage the sharpening surface at the most advantageous angle, and to this end they are arranged at the entrance of the V-groove at diametrically opposite points as shown clearly in Fig. 2 there being sufficient space for the knife to pass with limited amount of play. In order further to insure that the operator shall always insert the knife in the proper position there may be substituted for the members *f* a guide 20 (shown particularly in Fig. 4) consisting of a dome or cover *i* formed with cross slots *k* therein for the reception of the knife. The dome or cover may be of metal wood or other suitable material, and instead of 25 the dome or cover the guide may be in the form of a rim of wood or other suitable material surrounding the disk or wheel and having slots appropriately placed so as to receive the knife to be sharpened and guide 30 and hold the same to and against the sharpening surface of the disk or wheel. By these means the desired angularity of the knife relatively to the sharpening disk or wheel is assured.

35 In using the device the knife is inserted in the V-groove by passing the same into one of the slots *k* or between the members *f*, so that the knife blade bears against opposite sides of the said members, and drawn 40 across the surface of the disk or wheel *a*, the operator using a reasonable amount of pressure in so doing. Having thus drawn the knife across the wheel *a*, the operation may be repeated a few times and then the 45 knife is passed into the other slot *k* or against the other sides of the members *f* and the operation of drawing the knife across the disk repeated a few times and so on until the desired sharpness has been obtained. By alternately subjecting the knife 50 to the opposing sharpening faces of the disk a very even cutting edge is insured.

The device will be found eminently adapted for use in sharpening what are 55 termed "stainless steel knives" as owing to the nature of the sharpening disk the latter is enabled to act only upon the cutting edge, thereby causing no damage to the surface of the blade.

60 When constructed of carborundum, I have observed that the disks are not detrimentally affected by grease and when dirty they can be readily removed from the shaft or spindle

and by subjecting them to heat they may be easily cleaned.

65

What I claim and desire to secure by Letters Patent of the United States is:—

1. A machine for sharpening knives by reciprocating the blade upon the sharpening surface so as to rotate the same, comprising 70 rotatable beveled grinding disks having a spacing washer of leather between said disks, a support for said disks, and a pair of rotatable guides disposed tangentially at diametrically opposite points to enter the 75 V-groove constituted by the beveled portions of said disks.

2. A machine for sharpening knives by reciprocating the blade upon the sharpening surface so as to rotate the same, comprising 80 a pair of oppositely beveled grinding disks, a spacing washer between said disks, a rotatable shaft whereon said disks are mounted, clamping members for securing the disks and intermediate washer in 85 close relation upon said shaft, a support for said shaft and disks and a pair of rotatable guides disposed tangentially at diametrically opposite points of said disks and entering the V-groove constituted by the 90 beveled portions of said disks.

3. A knife sharpening machine, comprising 95 a shaft; grinding means fixed to said shaft and having a V-shaped peripheral groove; and means for guiding the knife blade into frictional engagement with both walls of said groove at a predetermined angle, whereby the reciprocation of the knife will positively rotate the grinding means with relation thereto.

100

4. A knife-sharpening machine, comprising 105 a shaft; a pair of grinding disks having oppositely-beveled faces which conjointly form a V-shaped groove; a spacing washer intermediate said disks; means for clamping said disks and washer together in close relation on, and securing them to, said shaft; and means for guiding the knife blade into frictional engagement with both walls of said groove, at a predetermined angle, whereby the reciprocation of the knife 110 will positively rotate said disks with relation thereto.

105

5. A knife sharpening machine, comprising 115 a shaft; grinding means fixed to said shaft and having a V-shaped peripheral groove; and means located at the open ends of said groove and at diametrically opposite points for guiding the knife blade into frictional engagement with both walls of said 120 groove at a predetermined angle, whereby the reciprocation of the knife will positively rotate the guiding means with relation thereto.

120

ALFRED CORNELL.
